Inventor
William A. Speer

UNITED STATES PATENT OFFICE.

WILLIAM A. SPICER, OF PROVIDENCE, RHODE ISLAND.

DESIGN FOR A COOKING-STOVE.

Specification forming part of Design No. 5,263, dated September 12, 1871.

To all whom it may concern:

Be it known that I, WILLIAM A. SPICER, of the city and county of Providence and State of Rhode Island, have invented and produced a new and original Design for Stove, of which the following is a specification:

The nature of my design is fully represented in the accompanying photographic illustration, to which reference is had.

I claim as my invention the design for a stove, as shown.

Witnesses: WILLIAM A. SPICER,
SIMON L. LAPHAM,
HENRY W. ALLEN.
